UNITED STATES PATENT OFFICE.

WILLIAM E. P. DEVANE, OF ADEL, GEORGIA.

NUT-LOCK FOR RAIL-JOINTS.

1,097,918.

Specification of Letters Patent. Patented May 26, 1914.

Application filed June 20, 1913. Serial No. 774,922.

To all whom it may concern:

Be it known that I, WILLIAM E. P. DEVANE, a citizen of the United States, residing at Adel, in the county of Berrien and 5 State of Georgia, have invented a new and useful Nut-Lock for Rail-Joints, of which the following is a specification.

The present invention appertains generally to nut locks, and relates more particularly to devices of that character applicable 10 to rail joints, for locking the nuts against accidental loosening.

It is the object of the present invention to provide a novel and improved device of that 15 character, which shall be comparatively simple, durable, and inexpensive in construction, which may be conveniently and quickly applied to a rail joint for locking the nuts against retrograde movement, and which 20 shall carry out its functions in a highly efficient and simple manner.

With the foregoing and other objects in view, which will be apparent as the nature of the invention is better understood, the 25 present invention resides in the combination and arrangement of parts and in the details of construction hereinafter described and claimed, it being understood that changes in the precise embodiment of the 30 invention herein disclosed can be made within the scope of what is claimed without departing from the spirit of the invention.

The invention has been illustrated in its 35 preferred embodiment in the accompanying drawing, wherein:—

Figure 1 is a perspective view of the rail joint embodying the improved locking device. Fig. 2 is a cross section of the joint, 40 taken through one of the bolts. Fig. 3 is a cross section of the joint, taken through one of the locking tongues or catches. Fig. 4 is a sectional detail of one of the locking tongues or catches, taken through the loop 45 or finger hold thereof.

As illustrated, the meeting ends of the rails 1—1 are connected by the angle iron fish plates 2—2, the usual bolts 3 being passed through the fish plates and webs of 50 the rail, and having the nuts 4 threaded thereon for clamping the fish plates against the rails. It is to be understood that any number of bolts may be employed, the present invention being applicable to joints em-

bodying any number of bolts, with equal 55 propriety or success.

In carrying out the present invention, there is provided a washer plate 5, preferably of sheet metal, which is clamped between the nuts 4 and the respective fish plate 60 2, the elongated washer plate 5 being provided with openings for the passage of the bolts.

Tongues 6 project from the upper edge 65 of the plate 5 and are bent back thereon, the tongues being preferably bent into compound curves with their free ends depending. A tongue 6 is preferably employed for each pair or set of nuts 4, although any number of tongues or catches 6 may be employed, according to the circumstances. The tongues or catches 6 are resilient or flexible 70 in order that their depending free ends may be raised when desired.

Each of the tongues or catches 6 is provided with an integral strap 7 projecting from one edge intermediate its ends, the strap 7 being bent upwardly over the intermediate portion of the tongue and then being bent under the tongue, to provide a loop 75 forming a finger hold, which will facilitate raising the free end of the tongue or catch.

In conjunction with the washer plate 5 having the catches, there is employed a locking bar 8, which is preferably wedge shaped 85 in cross section. The locking bar 8 is adapted to be inserted under the nuts 4 so as to wedge between the lower sides of the nuts and the lower flange of the respective fish plate 2, to lock the nuts against rotation. 90 The catches 6 are engageable with the locking bar 8 to maintain the same in position, the bar 8 being provided with notches 9 in its outer edge, with which the free ends of the catches are engageable, to lock the bar 8 95 against longitudinal and lateral movements.

In practice, it will be apparent that the washer plate 5 and locking bar 8 are readily applicable to a rail joint, the plate 5 being clamped under the nuts, the bar 8 being inserted underneath the nuts, and the catches 6 being raised to permit the bar 8 to be readily inserted under the nuts. When the bar 8 is slid to position under the nuts, the catches 6 will snap into the notches of the locking bar, 100 and consequently the bar will be held in position, so as to prevent the accidental displacement thereof. The bar 8 may be readily re-

5 moved, however, by simply raising the catches 6, this being facilitated by the loops or finger holds 7. When the locking bar 8 is removed, the nuts may be readily loosened or tightened without interference.

Having thus described the invention, what is claimed as new is:—

- 10 1. A nut lock for rail joints embodying a plate adapted to be clamped between the nuts and fish plate, and a wedge bar insertible underneath the nuts to prevent them from rotating, the said plate having a yieldable catch, and the wedge bar having a notch for the engagement of the catch.
- 15 2. A nut lock for rail joints embodying a washer plate adapted to be clamped under-

neath the nuts and having a resilient tongue bent back from its upper edge, and a locking bar insertible underneath the nuts to prevent them from turning, the said bar having a notch for the engagement of the free end of the tongue, the said tongue having a strap extending from one edge intermediate its ends, and the strap being bent around the tongue to provide a looped finger hold.

20 25 In testimony that I claim the foregoing as my own, I have hereto affixed my signature in the presence of two witnesses.

WILLIAM E. P. DEVANE.
